ARTIST'S PALETTE

Elise Ford, New York, N. Y.

Application June 28, 1941, Serial No. 400,241

1 Claim. (Cl. 41—5)

This invention relates to an artist's palette.

An object of my invention is to provide a palette that can be supported in a balanced condition on the arm.

Another object is to provide a palette that will not slip off the arm.

A further object is to provide a palette that is attractive in appearance.

A still further object is to provide a palette that is simple in construction and inexpensive to manufacture.

The improved palette is illustrated in the accompanying drawing in which—

Fig. 1 is a view of my improved palette positioned on the arm.

Fig. 2 is a plan view of the improved palette.

The improved palette has a flat body portion 5 formed of wood or other suitable material and is substantially rectangular in shape. One of the short edges is provided with a cut-away portion or recess 6 and spaced inwardly from said recess and within a hand's reach thereof is a thumb opening 7.

Along one of the long edges of the body is formed a recess 8. The wall of this recess at the end thereof closest to the thumb opening 7 is provided with a shoulder or nose portion 9.

In use, the palette is positioned on the arm 10 with the thumb through the opening 7 and the fingers around and gripping the wall of the recess 6. The forearm is positioned in the recess 8 so that the nose portion 9 interlocks therewith. When in this position, the palette is in proper balance on the arm and is prevented from slipping off by the nose 9.

I claim:

15 An artist's palette comprising a substantially rectangular body portion having one of its short edges formed with a recess and a thumb opening adjacent thereto and formed with a recess along one of the long edges sufficiently large to receive the forearm of the user and a nose portion formed at the end of said recess nearest the thumb opening to prevent the body portion falling off the forearm.

ELISE FORD.
